UNITED STATES PATENT OFFICE

94,363

DESIGN FOR AN ELECTRON DISCHARGE DEVICE

Bernard Salzberg, East Orange, N. J., assignor
to R C A Radiotron Company, Inc., a corpora-
tion of Maryland

Application October 31, 1934, Serial No. 53,826

Term of patent 14 years

To all whom it may concern:

Be it known that I, Bernard Salzberg, a citizen of the United States, residing at East Orange, in the county of Essex, State of New Jersey, have invented a new, original, and ornamental Design for an Electron Discharge Device, of which the following is a specification, reference being had to the accompanying drawing, forming a part thereof.

Figure 1 is a perspective view of an electron discharge device embodying my invention; Figure 2

is a plan view of an electron discharge device shown in Figure 1; and Figure 3 is a side elevation of the electron discharge device shown in Figures 1 and 2.

The solid black lines of the figures of the drawing show the dominant features of the design.

I claim:

The ornamental design of an electron discharge device as substantially shown and described.

BERNARD SALZBERG.
